CHAIR

Kayomi Watari, 643 N. Flores St.,
Los Angeles, Calif. 90048

Filed Nov. 1, 1967, Ser. No. 9,241

Term of patent 14 years

U.S. Cl. D15—1
Int. Cl. D6—01

FIG. 1.

FIG. 2.

FIG. 3.

FIG. 4.

FIG. 5.

FIG. 1 is a front perspective view of a chair showing my design;

FIG. 2 is a side view;

FIG. 3 is a front view;

FIG. 4 is a back view; and

FIG. 5 is a top view.

The design is characterized by the specific configuration and arrangement of the paired front leg members in their association with the similarly configured turned-wood hand rest portions, all as shown.

I claim:

The ornamental design for a chair, as shown and described.
